(No Model.)

A. FISCHER.

TAP HOLE BUSH.

No. 320,862.

Patented June 23, 1885.

UNITED STATES PATENT OFFICE.

ADOLPH FISCHER, OF RAVENSWOOD, NEW YORK.

TAP-HOLE BUSH.

SPECIFICATION forming part of Letters Patent No. 320,862, dated June 23, 1885.

Application filed April 23, 1885. (No model.)

To all whom it may concern:

Be it known that I, ADOLPH FISCHER, a citizen of the United States, residing at Ravenswood, in the county of Queens and State 5 of New York, have invented new and useful Improvements in Taps and Tap-Hole Bushes, of which the following is a specification.

This invention relates to taps and tap-hole bushes; and it consists in the novel construction 10 and combination of devices hereinafter described and claimed, reference being made to the accompanying drawings, illustrating my invention, in which—

Figure 1 represents a longitudinal section. 15 Fig. 2 is a transverse section in the plane $x-x$; Fig. 1. Fig. 3 is a side view of my tap-hole bush, showing its sections detached.

Similar letters indicate corresponding parts.

In the drawings, the letter A designates the 20 inner section of my tap-hole bush, and B is its outer section. This outer section consists of a tubular shank, b, which is provided with an internal screw-thread, and with a flange, b', at one of its ends. The outside diameter 25 of the shank b is somewhat less than the diameter of the tap-hole, so that said shank can be readily passed into the tap-hole. The flange b' is provided with holes for the reception of a screw-wrench, and the barrel-head is 30 provided with a recess to receive the flange b, so that when the tap-hole bush is in position the surface of the barrel-head remains smooth, which is a great advantage in cleaning, transporting, and otherwise manipulating 35 the barrel, and which is necessary on account of the revenue-stamp which has to be placed over the tap-hole.

The section A of my tap-hole bush consists of a tubular shank, a, which is provided with 40 an external screw-thread, and with a flange, a', at one of its ends. The internal screw-thread of the shank b of the section B and the flange a' are provided with holes for the reception of a suitable wrench.

45 In the barrel-head is a recess for the reception of the flange a', and if the two sections A B are introduced into the tap-hole in opposite directions and screwed up tight, both the inner and the outer surfaces of the barrel-head remain smooth.

The inner section, A, of my tap-hole bush is provided with an internal screw-thread to receive the stem c of the valve C, said stem being hollow and provided with an external screw-thread to fit the thread in the section A. 55

In the valve-stem c is formed a spiral slot, d, and when the valve is screwed into the position shown in Fig. 1 the liquid contained in the barrel flows out through this spiral slot. The pitch of this spiral slot is different 60 from that of the screw-thread, so that by the operation of opening and closing the valve the slot is kept clean.

I am aware that valves similar to mine have been combined with tap-hole bushes; 65 but such valves are provided with round holes in their tubular stems, and these holes are liable to clog up after a short time. The spiral slot in my valve-stem is self-cleaning and not liable to clog up, and since the valve cannot easily be taken out after the tap-hole bush has been secured in position a great advantage is gained by the spiral slot.

The tap or faucet D is provided with a screw-thread to engage with the internal screw-thread in the section B of the tap-hole bush, and in the inner end of the shank of said tap is formed a square socket, d', Fig. 2, to engage 75 with a square, e, formed at the inner end of the valve-stem c.

On the valve-stem is formed a stop, f, which prevents the valve from being screwed in beyond the desired limit. This stop co-operates with a shoulder, k, formed by the inner end 80 of the section A of the tap-hole bush.

On the shank of the tap D is fitted a hand-wheel, E, the hub of which forms a nut, g. On the inner face of this nut is placed a packing-disk, h, and when said nut is screwed up against the flange b' of the tap-hole bush a 90 tight joint is formed, and leakage at the outer end of the tap-hole bush is prevented.

What I claim as new, and desire to secure by Letters Patent, is—

1. A tap-hole bush consisting of the following elements, to wit: the internally-screw-threaded shank b, having the lateral flange b' at its outer end, the externally and internally screw-threaded shank a, provided with the lateral flange a' at one end and having its other 100

end terminating adjacent to the center of the shank *b*, to constitute a stationary annular stop, *K*, and a screw-threaded valve-stem, *c*, fitting the shank *a*, and provided at one end with a valve, *C*, and at its other end with an attached laterally-projecting stop to abut the shoulder formed by the end of the shank *a*, substantially as and for the purposes described.

2. The combination, with the tap-hole bush *10* and with the internal screw-thread formed therein, of the valve *C*, having a screw-thread

formed on its tubular stem to engage with the internal screw-thread of the tap-hole bush, and the spiral slot *d*, formed in the valve-stem, substantially as shown and described.

In testimony whereof I have hereunto set my hand and seal in the presence of two subscribing witnesses.

ADOLPH FISCHER. [L. S.]

Witnesses:

W. HAUFF,
E. F. KASTENHUBER.
